Samuel Lane

Letters Patent

X 5964

The subject referred to in these Letters Patent and making part of the same containing a description in the words of the said Samuel Lane himself of his improvement in the mode of using Horse Power called the Endless Chain Rail-Road.

To all persons to whom these presents shall come, Greetings. I do it know that I the said Samuel Lane have invented constructed & applied to use a road made of using Horse power by means of an endless chain, said road, called the, Endless Chain Rail way Horse Power. It consists of the accompanying plates & specified in the words following to wit. Take round rods of iron of any convenient size & length, those which I find best ^{are} of an inch in diameter & twenty inches in length. at space of an inch and three quarters on each end is turned down to $\frac{1}{8}$ of an inch making a smooth angle or guagon. I put each iron rolled one inch & three quarters diameter $1\frac{1}{2}$ of an inch thick & turned round & smoothed. Each collar takes up $\frac{1}{4}$ of an inch of the guagon. on the part projecting thro' the collar. I put a clasp of iron $\frac{1}{8}$ of an inch thick, for rods to a clasp, on the out side of these clasps. I put another set in such a manner that they break points. see fig 1 & fasten them on by means of a pin thro' the guagon. This connects the rods together by found a chain, by connecting the two extremities the chain becomes endless. Two iron wheels are then prop. and if any diameter adies & flat to receive the rods see fig 2. then according to a frame of the endless chain put them. It is best to have one of these drawn a little smaller than the other. said to make a slight ascent. Between the two iron wheels is an iron plate resting on a wooden post or beam which forms a coil way upon which the axle friction will move when in operation see fig 3. is the railway. the size of the rods will be necessary

be used to suit the wishes of those who use them. I have generally found the size above described convenient for all purposes to which I have put them. Place the rods $\frac{7}{16}$ of an inch apart, this leaves sufficient space for the cork of the horse shoe to go between them and prevent his slipping. As the size of the wheel 18 inches diameter has been found very convenient for quick motion. I do not claim the wheel chair, or the rotary horse power, (as it is sometimes called) as my invention. But I claim the invention of making this chain of round rods of iron. & I claim the mode of using the anti-friction rollers in the manner described, viz, by attaching them to the ends of the rods & placing a railway beneath them. I also claim the mode of connecting the rods together by clamps as above described. In testimony that the above is a true specification of my said improvement as above described. I have here set my hand and seal this 16th day of April in the year of our Lord 1838.
